(57) **CLAIM**

The ornamental design for neck pillow as shown and described.

DESCRIPTION

FIG. 1 is an isometric view of neck pillow showing my new design;

FIG. 2 is a front elevational view thereof of FIG. 1;

FIG. 3 is a rear elevational view thereof of FIG. 1;

FIG. 4 is a right side elevational view thereof of FIG. 1;

FIG. 5 is a left side elevational view thereof of FIG. 1;

FIG. 6 is a top plan view thereof of FIG. 1;

FIG. 7 is a bottom plan view of thereof of FIG. 1; and,

FIG. 8 is a perspective view of the neck pillow in a condition of use.

The cross-hatched shading is fragmentally shown for convenience of illustration, it being understood that the cross-hatched shading is uniformly continued over the surfaces on which it appears.

The broken lines are included for the purpose of illustrating environmental subject matter that forms no part of the claimed design.
